(57) **CLAIM**

The ornamental design for a controller for an electronic device, as shown and described.

DESCRIPTION

FIG. 1 is a front-top-right perspective view of a controller for an electronic device according to my new design;

FIG. 2 is a rear-bottom-left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a partial front-top-right perspective view thereof as indicated in FIG. 1.

The dot-dot-dash broken lines indicate the boundary of the enlarged portions of the drawings. The remaining broken lines in the figures depict portions of the controller for an electronic device. The broken lines form no part of the claimed design.
